ALBIN J. NOTT, OF NEW YORK, N. Y.

SURFACE CONDENSER

Application filed May 14, 1929. Serial No. 363,067.

This invention relates to surface condensers of that type in which tubes extend through a condensing chamber and communicate with water heads located at the opposite ends of the condensing chamber.

In order to compensate for the longitudinal expansion and contraction of the tubes, it is commonly the practice to permanently seal the tubes at one end in one of the partition walls between the condensing chamber and water head and to provide individual packings or stuffing boxes for the tubes in the opposite partition wall or tube sheet. This means, however, has been found to be open to certain objections, notably, the difficulty of gaining access to the stuffing boxes or packings for maintaining a fluid tight joint.

The present invention, therefore, broadly comprehends a surface condenser in which the tubes are permanently sealed at both ends in the tube sheets and in which one of the tube sheets is axially movable within the drum or body of the condenser to compensate for longitudinal contraction and expansion of the tubes.

The invention further embodies in a surface condenser as previously set forth, a packing interposed between said movable tube sheet and the drum by virtue of which an effective fluid tight seal is established to positively preclude the cooling medium from entering the condensing chamber.

As a further object, the invention embodies means for maintaining the packing in an effectual moistened condition by the introduction of condensate thereto.

More specifically, the invention aims to provide an improved surface condenser which includes a drum having at one end thereof a fixed tube sheet and a water head covering the same and in which the water tubes are permanently sealed in said tube sheet and a movable tube sheet having a marginal wall or flange which is mounted within the opposite end of the drum for axial movement and into which latter tube sheet the opposite ends of the tubes are permanently sealed together with an enlarged extremity at the latter end of the drum extending beyond the movable tube sheet with a water

head secured to and covering said enlarged extremity of the drum.

Other objects of the invention reside in the comparative simplicity of construction of the condenser, the economy with which it may be produced and maintained in a fluid tight condition and the general efficiency derived therefrom.

With the above recited and other objects in view, reference is had to the following description and accompanying drawings, in which there are exhibited several examples or embodiments of the invention, while the claims define the actual scope of the same.

In the drawings:

Figure 1 is a longitudinal sectional view through a surface condenser constructed in accordance with the invention.

Figure 2 is a transverse sectional view therethrough taken approximately on the line indicated at 2-2 in Figure 1.

Figure 3 is a fragmentary enlarged longitudinal sectional view.

Figure 4 is a view similar to Figure 3, illustrating a slightly modified adaptation of the invention.

Figure 5 is a fragmentary sectional view through a modified form of the lantern gland employed in the packing.

Referring to the drawings by characters of reference, 10 designates the body or drum of the condenser which is preferably of cylindrical formation and which has secured over one end, a fixed or stationary tube sheet 11 and a head 12, which head 12 and tube sheet 11 define a cooling medium or water compartment 13. A movable tube sheet 14 provided with a marginal wall or flange 15 is mounted within the opposite end of the body or drum 10 for axial movement, and said body or drum, together with the tube sheets 11 and 14, defines a condensing chamber 16 into which the steam is introduced through the inlet 17 and from which the condensate is removed through an outlet 18. Tubes 19 extend through the condensing chamber and their opposite ends 20 and 21 are permanently sealed in the respective tube sheets 11 and 14 in any approved manner, such as by being expanded, belled, welded or brazed. movable or floating tube sheet 14 compensates for contraction and expansion of the tubes 19 which occurs due to fluctuation in temperature. In the preferred form of the invention illustrated in Figures 1 to 3, inclusive, the end of the drum 10 within which the floating tube sheet is arranged is provided with a terminal or extremity 22 of larger diameter than its major portion, which terminal or extremity has attached to its free end a covering head 23 defining together with said terminal or extremity 22 and tube sheet 14, a water head or cooling medium compartment 24. In order to seal the outer and inner relatively movable peripheries of the flange or wall 15 of the tube sheet 14 and the drum or body 10 to prevent the passage of fluid from the compartment 24 to the condensing chamber 16 or vice versa, a stuffing box is employed in which are arranged the packing rings 25 which may be compressed by a gland 26 upon removal of the head 23 to compensate for wear on the packing rings. In order to properly maintain the packing rings 25 in a moistened condition, a lantern gland 27 is employed which is interposed between the packing rings and which is designed to receive and distribute either pure water from a water supply or condensate thereto, which water supply or condensate is obviously under a pressure exceeding the pressure of the circulating cooling water and which condensate is received preferably from the condensate conduit 28 by means of a branch conduit 29.

In the modified adaptation of the invention illustrated in Figure 4, the marginal wall or flange 15 of the tube sheet 14 extends outwardly beyond the end of the drum or body 10 and directly receives the covering head 23 so that the water head or cooling fluid compartment 24 is defined between the tube sheet 14, covering head 23 and flange 15. In this instance, the packing nut 26 is exteriorly disposed whereby access is had thereto for the purpose of adjustment or repacking without the necessity of removing the covering head 23.

The lantern gland 27 may either be provided with a single web 30, as illustrated in Figures 3 and 4, or with a double web 31, as illustrated in Figure 5, the latter being designed for heavy duty.

From the foregoing, it will thus be seen that a surface condenser has been devised which insures a positive exclusion of the cooling medium from the condensing chamber without the necessity of resorting to the use of individual packing glands or stuffing boxes for the tubes and the trouble and time involved in maintaining the same in a fluid tight condition.

What is claimed is:

1. A surface condenser including a drum, tubes extending therethrough, tube sheets

with which the tubes are permanently sealed, one of the tube sheets being axially movable within the drum to compensate for longitudinal contraction and expansion of the tubes, a packing interposed between the movable tube sheet and that portion of the drum with which the movable sheet engages and means for introducing condensate from the condenser to the packing for maintaining the same in a moist condition.

2. A surface condenser including a drum, tubes extending therethrough, tube sheets with which the tubes are permanently sealed, one of the tube sheets being axially movable within the drum to compensate for longitudinal contraction and expansion of the tubes, a packing interposed between the movable tube sheet and that portion of the drum with which the movable sheet engages and means for introducing pure water to the packing for maintaining the same in a moist condition to render the packing effective.

3. A surface condenser including a drum, tubes extending therethrough, tube sheets with which the tubes are permanently sealed, one of said tube sheets being axially movable within the drum to compensate for longitudinal contraction and expansion of the tubes, a packing interposed between the movable tube sheet and that portion of the drum with which the movable tube sheet engages and means for introducing pure water or condensate under a pressure exceeding the circulating cooling water of the condenser to moisten and maintain the packing in a fluid tight condition.

Signed at New York, in the county of New York and State of New York this 13th day of May, A. D. 1929.
